(57) **CLAIM**

The ornamental design for a coffee maker as shown and described.

DESCRIPTION

FIG. 1 is a top front side perspective view of a coffee maker showing my new design;

FIG. 2 is a front view of the coffee maker;

FIG. 3 is a rear view of the coffee maker;

FIG. 4 is a left side view of the coffee maker;

FIG. 5 is a right side view of the coffee maker;

FIG. 6 is a top view of the coffee maker; and,

FIG. 7 is a bottom view of the coffee maker.

The broken lines shown in the drawings represent parts of the coffee maker that form no part of the claimed design.

1 Claim, 7 Drawing Sheets
